(57) **CLAIM**

The ornamental design for a table, as shown and described.

DESCRIPTION

FIG. 1 is a perspective view of the table;

FIG. 2 is a front elevational view of the table, the rear, left side and right side elevational views of which are identical;

FIG. 3 is a top plan view of the table; and,

FIG. 4 is a bottom plan view of the table.

The broken lines depict portions of the article that form no part of the claimed design.
